METHOD OF STEAM-HEATING.

1,221,433.

Specification of Letters Patent.

Patented Apr. 3, 1917.

Original application filed January 5, 1910, Serial No. 536,504. Divided and this application filed May 28, 1913, Serial No. 770,293.

To all whom it may concern:

Be it known that I, JAMES L. FITTS, citizen of the United States, and resident of Pensauken township, county of Camden, 5 and State of New Jersey, have invented an Improvement in Methods of Steam-Heating, of which the following is a specification.

This application is a division of my application Serial Number 536,504, filed January 5, 1910, and has particular reference to the method of steam heating described therein, said prior application being specifically directed to the apparatus in which the method is carried out.

15 My invention has particular reference to a method of steam heating in which low pressure steam is employed and in which the water of condensation is returned to the boiler by gravity; and the object of my invention is to provide a system which shall automatically, during the normal operation of the heating system, permit the escape of air to the atmosphere, but which will prevent the escape of water of condensation 20 from the apparatus in case of abnormal operating conditions, such as an excessive boiler pressure existing in the system.

More specifically, the object of my invention is to provide a gravity system of 30 steam heating which at all times in normal operation is adapted to permit the air from the system to escape but without loss of steam or water, and to maintain these results irrespective of abnormal temporary 35 conditions in the steam pressure of the boiler. The object of my invention may therefore be stated to provide means which will automatically cause the steam heating apparatus to provide a constant differential 40 between the pressure in the steam supply and the return pipe, said constant differential maintaining a definite static head on the return side, even where the steam pressure in the boiler is reasonably varied.

45 My invention consists of certain improvements which are fully described hereinafter and more particularly defined in the claims.

Referring to the drawings: Figure 1 is a 50 diagrammatic elevation of a steam heating apparatus adapted for use in carrying out the method embodying my invention; and

Fig. 2 is a sectional elevation of the automatic control valve used therein.

2 is the boiler, and 3 are the steam mains leading therefrom and extending upward 55 through the building in the form of risers and by which steam is supplied to the various radiators or heating coils 4 under the control of hand regulated or modulation valves 5 of any suitable construction. A 60 suitable form of these modulation valves is shown in Letters Patent No. 939,823 granted to me on November 9, 1909, and in which there is a rotatable plug controlling ports of different sizes to deliver more or 65 less steam to the radiator as may be required. Any other suitable form of valve for this purpose may be employed. 6 are return pipes leading from the various radiators or coils and are arranged to discharge 70 at the bottom into a receiving tank 10 located at an elevation above the normal water line of the boiler 2. From the bottom of the receiving tank 10 the water is returned to the boiler by a pipe 9 connecting with its lower part directly or 75 through a check valve structure 8, which permits the flow of water into the boiler, but prevents the flow in the reverse direction. Sometimes check valves are employed, 80 and at other times they are omitted and in this latter case the communication between the boiler and the tank 10 is free and open.

7 are automatic valves of any suitable character for permitting the passage of air 85 and water from the radiators 4 into the return pipes 6, but preventing or restricting the passage of steam. Numerous types of automatic valves adapted to steam heating apparatus are found upon the market, and 90 any of these may be employed for the purposes of the valves 7, in carrying out the practice of my improved method. Opening from the upper part of the tank 10 is a vent pipe 11, preferably terminating in a 95 check valve 12, said valve operating to permit the escape of the air from the tank 10 and consequently from the heating system, and at the same time preventing the inflow of air in case of a partial vacuum from any 100 cause, such as when turning steam into cold radiators.

13 is an automatic valve device arranged in the pipe 11 and preferably between the tank 10 and the check valve 12, and operates automatically to control the pipe 11 to permit the escape of air, but prevent the escape of water, and therefore performs the function of retaining the water within the system, if from any abnormal cause the water tends to flow from the vent pipe into the atmosphere. The construction of this automatic valve 13 is shown in Fig. 2, and comprises a thoroughfare 17 arranged in the vent pipe 11 and controlled by the valve piece 18. The valve piece 18 is secured to a diaphragm 15 arranged as the sides of two chambers 19 and 20, the former being in communication with the tank 10 through a portion of the vent pipe 11, and the latter being in communication with the steam supply pipe 3 by means of a small pipe 14. Normally, the chamber 20 is kept full of water so that the steam from the pipe 3 does not directly act upon the diaphragm 15 but upon the body of water within the chamber 20, and therefore indirectly upon the diaphragm. The diaphragm 15 is also connected to a rod 21, working through a stuffing-box in the bottom of the valve device, and said rod is hinged at its lower part to a counterbalance lever 16 having adjustable weights which permit of any degree of adjustment necessary. This weighted lever acts as a mechanical device for adjusting the normal pressure, upon the diaphragm 15, so that it shall properly respond to variations in the differential in pressures of the steam pipe 3 and the tank 10 or return pipe.

In the normal operation of the heating system, the level of the water in the tank 10 is above the level of the water in the boiler 2 sufficiently to provide a static head to counterbalance the steam pressure carried in the boiler, and this may be, for example, 1 $\frac{1}{4}$ lbs., or any other low pressure, such as employed in low pressure steam heating systems. During the normal operation of the apparatus, the air is driven from the radiators 4 by the inflowing steam whose supply is regulated by the modulation valves 5, and said air finds its way through the return pipe 6 into the receiving tank 10, and thence through the vent pipe 11, valve 13 and check valve 12, into the atmosphere. The water of condensation, which is produced within the radiators, is automatically permitted to flow from the radiators into the return pipes 6 by the automatic valves or traps 7, whenever said water accumulates. This water of condensation flows through the return pipes into the tank 10 and thence by reason of the static head, returns to the boiler.

Should, however, the system become deranged from its normal condition of operation, such for instance, as by too much pres-

sure in the boiler, there will be danger of the water from the receiver tank 10 being forced outward through the vent pipe 11 into the basement or upon the floor of the building, producing not only an objectionable mess, but a more serious loss of water from the heating system and a variation of the differential between the steam supply and return sides of the system. This latter condition is particularly objectionable in an automatic gravity system, which is usually given but little attention. Whenever the boiler pressure increases abnormally, the water is not permitted to flow from the receiving tank 10 into it, because of the internal pressure which keeps the check valve device 8 closed; and consequently, the water of condensation passing from the radiators into the tank 10 will fill said tank and overflow through the pipe 11 if not otherwise prevented. Where the check valve device 8 is not employed, then the abnormal boiler pressure will force the water from the boiler through the pipe 9 into the tank 10 and thence outward through the vent pipe 11 if not prevented. The abnormal loss of water from any of these causes is liable to produce dangerous conditions in the system and a derangement of the normal working thereof.

By employing the automatic valve device 13 in the vent pipe 11, means is provided for maintaining the normal differential due to the static head and for automatically preventing the escape of water from the heating system under any of the abnormal conditions mentioned above.

In adjusting the apparatus, the weighted lever 16 has its weights so adjusted that the differential in pressures on opposite sides of the diaphragm 15 is such that the valve piece 18 will close the thoroughfare 17 when the receiving tank 10 becomes about half filled with water. In this way the vent pipe 11 will be closed by the valve device 13 before water enters the said vent pipe. This adjustment is due to the presence of a sufficient pressure in the supply pipe 3 to cause the water in the pipe 9 and tank 10 to give a head above the water level in the boiler, such as would maintain the tank 10 about half filled with water. This would be a greater head than the normal head required; and any higher pressure in the boiler, which would cause a head of water being sustained in the pipes 9 and 6 and tank 10, as would produce a discharge of water through the vent pipe 11 if not otherwise prevented, could not produce such discharge because the valve device 13 would hold the vent pipe closed and build up an air pressure in the return pipe 6 and tank 10 which would prevent the rise of water into the pipe 11. While this should prevent rise of the water above the tank in normal operation, it is

evident that if temporarily any water was forced into the vent pipe 11, the automatic valve 13 would prevent its escape. As soon as the pressure in the boiler is reduced to a 5 normal condition, the water in the pipe 9 and tank 10 will be lowered automatically by discharge into the boiler and the valve device 13 will instantly respond to open the vent pipe 11. It is evident that, if desired, 10 the check valve 12 may be omitted, though in practice I prefer that it shall be employed for reasons to be described.

The valve device 13, as before stated, operates under a differential in pressure, the 15 pressure below the diaphragm being the boiler pressure and that above the diaphragm being the pressure of the air and vapor in the return and practically atmospheric pressure. This atmospheric pressure 20 is maintained largely because of the use of the automatic valve 7 from the discharge side of the radiators, as said valves restrict the passage of steam so that the returns are of a lower pressure than the steam pressure 25 in the supply pipes 3. Any vapor in the returns is trifling in character when the valves 7 are properly constructed, and the normal pressure of said vapor is nominally that of the atmosphere, because the valve device 13 30 in the normal operation of the apparatus is open and the check valve 12 offers no resistance to discharge into the atmosphere.

While in the normal operation of the system, where the static head of water in the 35 return pipe 9 exactly balances the steam pressure in the supply pipe 3, it is evident that the valve device 13 may be normally open to permit escape of any air which may find its way into the tank and the vent pipe 11, and 40 which is brought down with the water of condensation from the radiators. Steam is not permitted to pass from the radiators into the return pipes 6 and thence into the tank 10, because of the presence of the automatic 45 devices or traps 7 which permit the free passage of water and air but restrict the passage of steam. As under these conditions we have a differential corresponding to atmospheric pressure on the return side and the 50 initial pressure of the steam on the supply side, there will be a constant flow of steam through the modulation valves 5 according to the requirements by the mere adjustment of the valves. In view of the fact that when 55 starting up the system with cold radiators or when any radiator is suddenly put into operation and a vacuum is produced therein, it is evident that this is only a temporary condition and one which would naturally tend 60 to draw air from the outside into the system, and the check valve 12 automatically acts to prevent the inflow of air under such conditions. This condition of vacuum, however, 65 does not impair the operation of the apparatus in the slightest, because the vacuum

wherever it may exist is upon the return side of the modulation valves 5, and consequently the system will operate as a perfect heating system in which the water will gravitate back to the boiler and the air which may be 70 temporarily retained to a greater or less extent in the radiator, will ultimately be driven into the return pipe under the differential between the pressures in the supply pipe and the return pipe. Conditions of 75 vacuum could only continue where the condensing capacity of the radiators would be greater than the supply of steam delivered to them, and while this is an abnormal condition for the operation of a system of this character, it is pointed out, however, that the 80 system, being a closed and tight one which prevents the inflow of air from the outside, will operate during the presence of the vacuum in an automatic manner with great 85 efficiency during the continuance of the said vacuum. The operation of the apparatus under a pressure greater than that corresponding to the predetermined static head, such as might occur by providing too great 90 a boiler pressure from any cause unintentionally or otherwise, will cause the circulation of the steam under the same differential, that is, equal to the predetermined static head due to the lower steam pressure, after 95 the disturbance caused in the system by the raising of the steam pressure has had an opportunity to readjust itself, and this may be explained as follows:

Assuming that instead of $1\frac{1}{4}$ pounds of 100 steam pressure, there was a 5 pound pressure, which with atmospheric pressure on the return side would make a differential of 5 pounds, which would support a static head of approximately ten feet of water, and 105 consequently the water would accumulate in the tank 10 and return pipe 6. As the increase in differential would cause the valve device 13 to automatically close the vent pipe 11, no water would be permitted to 110 escape. In a short time, the accumulations of air in the return pipe driven into it under the steam pressure admitted to the radiators, will build up a return pressure which will equal the excess of the differential over 115 the predetermined amount, and by reason of this, the water in the return pipe 9 will flow into the boiler and the water lowered in the return pipe 6 and receiver tank 10 until the predetermined static head is once more 120 established. This predetermined static head is maintained, because we now have only the $1\frac{1}{4}$ pounds as a differential although we have 5 pounds steam pressure and $3\frac{1}{4}$ pounds back pressure in the return. This condition 125 of the system is then exactly what it was originally when we had $1\frac{1}{4}$ pounds steam pressure and atmospheric pressure in the returns. As the governor valve 13 is adjusted to automatically maintain a differ- 130

ential of $1\frac{3}{4}$ pounds between the steam supply and the returns, it is evident that it will operate with 5 pounds pressure in the supply to maintain the differential of $1\frac{3}{4}$ pounds just the same as it would operate with the steam pressure of $1\frac{3}{4}$ pounds. In fact, it will operate the same with any variation in the steam pressure, once the system has rebalanced itself, and at no time will it permit any water to pass, because no water would tend to pass except when there was a greater differential than $1\frac{3}{4}$ pounds, and if the regulator or valve device 13 was set for that differential, it would not open the valve for any differential above that amount. It is seen therefore, that my improved system is self-regulating and automatic and maintains the circulation of the steam under a definite differential, irrespective of the steam pressure in the boiler; and this enables the system to be operated on the modulation principle in a perfectly controllable manner, for if the differential remains constant during normal operation of the system, the adjustment of the valve device will control the amount of heat which is to be given up by the radiators. It is therefore apparent that this system is responsive for variations in the steam pressure without derangement of the system and will maintain its operation at a predetermined differential irrespective of the variations in the steam supply pressure; and moreover, by the use of the automatic valve device 13 in the vent pipe, a constant operative static head may be employed to insure return of the water to the boiler by gravity for various steam pressures corresponding to said static head and above the pressure of the static head, this being a feature which is not found in any other system, as far as I am aware.

I have shown a form of automatic regulator or valve device 13 which is suitable for the purposes of my invention, but I do not restrict myself to the use of any particular form of such a device, as any construction of, what is commonly known as a reducing valve (similar in general construction to the valve device 13), may be used for the purposes of my improvements; and likewise, while I have shown a typical form of low pressure heating apparatus, I do not restrict myself to the details thereof, as these may be varied without departing from the spirit of the invention.

In this application, I make no claim to the apparatus herein shown and described, as that forms subject matter of my application of which this application is a division.

Having now described my invention, what I claim as new and desire to secure by Letters Patent, is:—

1. The herein described method of operating a gravity system of steam heating, which

consists in providing a predetermined static head provided by maintaining a normal differential in pressures between the supply and return sides of the system with the return side open to the atmosphere whereby the steam may be delivered into the radiators under a predetermined normal difference in pressures between the supply and return sides thereof, causing the water and air to pass from the radiators into the return side of the system while substantially preventing the passage of steam, and automatically controlling and preventing the escape of air from the return side of the system into the atmosphere when said normal differential in pressures in the supply and return sides of the system is exceeded whereby the air and water are retained in the return side of the system to build up an abnormal pressure whenever the steam pressure on the supply side exceeds a predetermined normal pressure corresponding to the normal static head in the return side, the operation being such that the air pressure added to the pressure due to the static head is made to balance the steam pressure on the supply side; and a constant operative differential in pressures above atmospheric pressure is maintained in the supply and return sides of the system for different boiler pressures.

2. The herein described method of operating a gravity system of steam heating, which consists in providing a predetermined static head on the return side for returning the water of condensation to the boiler said static head provided by maintaining a normal differential in pressures between the supply and return sides of the system with the return side open to the atmosphere whereby the steam may be delivered into the radiators under a predetermined normal difference in pressures between the supply and return sides thereof, causing the water and air to pass from the radiators into the return side of the system while substantially preventing the passage of steam, automatically controlling the escape of air from the return side of the system into the atmosphere when the steam pressure becomes abnormal said control being under the regulation produced by said normal differential in pressures in the supply and return sides of the system in such manner that the air and water are retained in the return side of the system to build up an abnormal pressure whenever the steam pressure on the supply side exceeds a predetermined normal pressure corresponding to the normal static head in the return side, and automatically causing all of the air in the return side in excess of that necessary to maintain this balance of pressures in the two sides of the system to escape out of the system, whereby the air pressure

added to the pressure due to the static head is made to balance the steam pressure on the supply side, and a constant operative differential in pressures above atmospheric pressure is maintained in the supply and return sides of the system for abnormal boiler pressures.

3. The herein described method of operating a gravity system of steam heating, which 10 consists in supplying steam from a boiler to the radiators and normally returning the water of condensation from the radiators to the boiler by gravity and under atmospheric pressure, maintaining a static head in the return portion of the system for the purpose of balancing the normal pressure in the boiler, substantially preventing the flow of steam from the radiator on the return side of the system whereby a given normal pressure 15 of air alone may be formed in the return part of the system between the radiator and down to the static head, and maintaining said differential of pressures between the normal boiler pressure and return air pressure 20 for all abnormal boiler pressures by a variable communication with the atmosphere on the return side of the system at a point between the static head and the radiators, said communication controlled by the varia-

tion of pressures in the supply and return 30 portions of the system and for all abnormal boiler pressures.

4. The herein described method of operating a gravity system of steam heating, which 40 consists in supplying steam from a boiler to the radiators under a predetermined normal pressure and normally returning the water of condensation from the radiators to the boiler by gravity and under atmospheric pressure, causing the water and air from the radiators to pass into the return pipe but preventing the passage of steam thereto, normally permitting the escape of the air to the atmosphere and delivering the water to the boiler, maintaining a static head on the return side of the system by the water in the return pipes to counterbalance the predetermined normal pressure in the boiler, and automatically sealing the escape of air and water to the atmosphere from the return 45 pipe under the control of an abnormal steam pressure created in the boiler.

In testimony of which invention, I hereunto set my hand.

JAMES LOGAN FITTS.
